ATTORNEY

UNITED STATES PATENT OFFICE.

WILLIAM J. LEWIS, OF DUNLAP, KANSAS.

WINDOW-SCREEN.

1,251,981.

Specification of Letters Patent. Patented Jan. 1, 1918.

Application filed September 25, 1916. Serial No. 122,106.

To all whom it may concern:

Be it known that I, WILLIAM J. LEWIS, a citizen of the United States, residing at Dunlap, in the county of Morris and State of 5 Kansas, have invented certain new and useful Improvements in Window-Screens, of which the following is a specification.

This invention has relation to window screens, and has for its object to provide a 10 window screen embodying a frame which may be made in various lengths to fit windows of various heights, and a screen section which is movable in a vertical direction within the same and adapted to be wound at 15 its upper end upon a spring roller after the manner of a curtain shade.

Another object of the invention is to provide a screen having the above named characteristics and means embodied in the frame 20 whereby the screen section may be retained against movement in any vertically adjusted position.

In addition to the foregoing, my invention comprehends improvements in the details of 25 construction, and arrangement of the correlated parts without departing from the spirit of the invention or the scope of the appended claim.

In the accompanying drawings in which 30 similar and corresponding parts are designated by the same characters of reference throughout the several views in which they appear;

Figure 1, is a view in front elevation of a 35 window screen constructed after the manner of my invention, and

Figs. 2, 3 and 4, are detail sections taken on the planes indicated by numerals corresponding to said figures in Fig. 1.

With reference to the drawings, 1 indicates generally the vertical frame members of my improved window screen, and 2 and 3 respectively the lower and upper end frame members connecting the ends of 45 the vertical members. The upper member 3 is formed with a horizontal transversely extended roller casing 4 formed of sheet metal or the like, having an opening 5 in its under side extending longitudinally 50 thereof.

Each of the frame members 1 as well as the frame members 2 and 3 are formed of parallel spaced sections 6 and 7, illustrated to advantage in Figs. 3 and 4, with their 55 outer longitudinal edges hingedly connected by the interengagement of lugs 8 and 9 pro-

vided on the sections 6 and 7 respectively. The frame members 1, 2, and 3 thus formed are provided at suitable intervals with transversely alined openings, the openings 60 in the member 7 being internally threaded to receive the correspondingly threaded end of a thumb screw, the shank of which is indicated at 10, and the head at 11, said head bearing against the outer surface of the 65 member 6. Each of the frame members 1, 2, and 3, is further provided with a series of transversely alined openings indicated at 12 for a purpose which will be presently obvious.

The ends walls 13 of the roller casing 4 provide support for the trunnion of a roller 14 conforming to the ordinary curtain shade roller having a spring therein, the trunnion being mounted within the end wall of the 70 casing to insure operation of the roller after the manner of a shade roller. The screen section indicated at 15 may be formed of flexible wire fabric, and in the present instance is provided upon each longitudinal 80 edge with a selvage indicated at 16, and formed by bending upon itself a strip of flexible material, which may be fabric or the like and secured to the wire fabric by stitching or otherwise. The lower end of 85 the wire fabric may be also reinforced in a similar manner by a binding strip 17. The screen section is rolled upon the roller 14, and the selvage edges thereof disposed within the space between the sections 6 and 7 of 90 the vertical frame members 1 of the screen frame. A handle is provided for the screen section in the form of a loop 18 of wire or the like secured to the binding strip 17 by means of a strip of metal 19 bent upon itself 95 about one of the members of the loop 18 and secured by rivets or the like to said binding strip. Obviously, by moving the screen section down by gravity in the handle, the roller 14 is caused to wind up against the 100 tension of the spring contained therein, and the fabric of the screen section 16 placed under strain. To retain the screen section in an adjusted position small metallic fastenings 20 are passed through one of the openings 12 in each of the vertical frame members 1 and into one of a series of openings 21 provided for that purpose in either binding strip 14 or the section 16 of the screen section. The screen may be further held 110 against displacement by turning the heads 11 of the set screws which extend through

the vertical members of the same for binding together the sections composing the same against the selvage edge of the screen section.

5 The frame of this window screen may be varied in length by removing for instance, the lower strip 2 from connection with the end of the frame members 1, severing said frame members 1 to a degree permitting the 10 same to fit within the vertical height of a window and reapplying the member 2 to the severed ends. Said frame members may be secured together by means of the fastenings 20, which are passed through openings of 15 the series indicated at 12. To facilitate adjustment of the frame to any size of window, it is preferable that the frame members be constructed of wood.

While I have illustrated and described my 20 invention with some degree of particularity, I nevertheless realize that in practice various alterations therein may be made, and I therefore reserve the right and privilege of changing the form of the details of con-

struction, or otherwise altering the arrangement of the correlated parts without departing from the spirit of the invention or the scope of the appended claim.

Having thus described my invention, what I claim as new and desire to secure by Letters Patent is:—

In a window screen, a frame including vertical side members and a lower horizontal connecting member, each member comprising a pair of strips, apertured ears on the strips, pins entering the ears to connect the strips for relative movement, one strip of each pair having a plurality of threaded openings, and the other strip having registering smooth openings, to receive screws 40 therein which also enter the threaded openings, whereby to clamp the strips together.

In testimony whereof I affix my signature in presence of two witnesses.

WILLIAM J. LEWIS.
